SHROUDING FOR LAWN MOWER ENGINE

Mario F. Fernandez, Minneapolis, Minn., assignor to The
Toro Company, Minneapolis, Minn.

Filed Aug. 9, 1974, Ser. No. 496,133

Term of patent 14 years

Int. Cl. D15—03

U.S. Cl. D40—1 B

FIG. 1

FIG. 2

FIG. 3

FIG. 4

FIG. 5

FIG. 1 is a top plan view of a shrouding for lawn mower engine embodying my new design;

FIG. 2 is a rear elevational view thereof;

FIG. 3 is a front elevational view thereof;

FIG. 4 is a left side elevational view thereof; and

FIG. 5 is a right side elevational view thereof.

The broken lines in the drawing are for illustrative purposes only.

I claim:

The ornamental design for a shrouding for lawn mower engine, as shown and described.
